UNITED STATES PATENT OFFICE.

ENGLAND J. BARKER, OF CHICAGO, ILLINOIS.

ATTACHMENT FOR TYPE-WRITERS, ADDING-MACHINES, AND THE LIKE.

1,140,493.

Specification of Letters Patent. Patented May 25, 1915.

Application filed January 2, 1914. Serial No. 809,848.

To all whom it may concern:

Be it known that I, ENGLAND J. BARKER, a citizen of the United States, residing in Chicago, in the county of Cook and State of Illinois, have invented certain new and useful Improvements in Attachments for Type-Writers, Adding-Machines, and the like, of which the following is a full, clear, and exact description.

My invention relates to attachments for supplying paper from a continuous roll or rolls to the platen of typewriting machines, adding machines, and the like. I am aware that this has been done before, and I am also aware that some of the attachments for accomplishing this result use devices for the purpose of feeding the paper at right-angles to the platen and keeping the same in register. Experience has shown that in some instances these devices resist the effort to rotate the platen on its own axis or resist the reciprocable movement of the carriage of the machine in which the platen is journaled, and cannot be relied upon, in some instances with certainty, to feed the paper at right angles to the platen and always in register with each other. The consequence of these defects is, particularly when manifold copies are being made, to cause the print on the manifold copies to get out of place, or "register," and often-times results in confusion that destroys the value of the manifold work as correct copies.

The principal object of my invention is to feed paper from one or more rolls having relatively stationary bearings, to the platen journaled in the transversely reciprocable carriage of a typewriting machine, or the rotatable platen of an adding machine, without twisting the paper strips to such an extent as to resist the movement of the carriage or get the said strips out of register with one another.

It is also an object of my invention to provide means for directing the movement of the paper strips to the platen at right-angles to the axis thereof, and it is a further object to rotate the rolls simultaneously with and to the same extent as the platen, so that the intermittent forward movement of the said strips will be the same in every instance regardless of the diameter or diameters of the roll or rolls.

These and other objects I accomplish by the means hereinafter fully described, and as particularly pointed out in the claims.

In the drawings: Figure 1 is a side elevation of a typewriting machine having my improvements applied thereto and the stationary rolls of paper strips, and support therefor, partially broken away to illustrate the operation of said improvements. Fig. 2 is a top plan view of the same. Fig. 3 is a fragmentary side elevation of a slightly modified form of my invention. Fig. 4 is a diagrammatic view of the loop of paper between the rolls and the platen and illustrating the twist of the same in two positions of the typewriter carriage.

For the purpose of convenience, I have herein illustrated and described my improvements applied to a standard typewriting machine of the "visible" type, but my improvements are equally applicable to other makes of typewriters of the non-visible type, as well as to adding and billing machines, and to combined typewriting and adding machines of the usual design, or to book-typewriters wherein the platen is a flat stationary plate over which the writing mechanism is moved.

My invention, as shown in the drawings, comprises, in combination, a typewriting machine A, a table or desk B upon which said machine is mounted, and a rack or frame for journaling one or more rolls of paper strips, together with mechanism for connecting and accomplishing the coöperation of these three principal elements.

The typewriting machine may be of any of the standard construction, as above mentioned, having a revolute platen 2 journaled in a transversely reciprocable carriage 3, and the table or support for this machine may be of any suitable construction having a false top 4 that extends a considerable distance to the rear side thereof and is provided with a transverse slot 5 therein a suitable distance back of the rear of the desk.

The frame for journaling the rolls of paper strips or "records," to be used in the typewriting machine, comprises two vertical uprights 6, 6, arising from the rear extension of the top of the desk just back of the slot 5 therein, and suitably braced by braces 7, 7. These frames are separated a suitable distance apart and are provided with forwardly projecting lugs 8, 8, in which the journals of the rollers 9 upon which the record-rolls 10 are wound.

In Fig. 1 of the drawings, five of these record-rolls are shown to be journaled, one

above the other, in uprights 6, 6, and the record strips are drawn downward therefrom in the same vertical plane through slot 5 in the rear extension of the top of the desk to a point very near the floor and then said record strips are extended vertically up through said slot 5 to a point slightly above the plane of the typewriting machine where they are passed between guide-rollers 11, 11, and their course changed in a horizontal direction to a series of idle-rollers 12, 12, that separate each record from the others and direct them in a downward direction to and under the platen of the typewriting machine, for the convenient engagement of the type.

Guide-rollers, 11, 11, are secured in upright frames or posts 13 secured to and arising from the rear ends of the extensions or bars 14, 14, the forward portions of which latter are screwed or otherwise attached to the side-frames 15, 15, of the carriage 3.

Idle-rollers 12, 12, are journaled in standards 16 secured to and arising from said bars 14 at the rear of the carriage.

The principal feature of my invention is the stretch of slack record strips between the feed rolls and the typewriting machine. The maintenance of this slack during the operation of the typewriting machine is essential. In order to accomplish this it is necessary to provide means for transmitting the rotary movement of the platen to the rolls of paper, and to do this without said transmission means being affected by the longitudinal movement of the carriage. Said means comprise a shaft 17 whose axis is horizontal and parallel to the axis of the platen and which is located to the rear of the typewriting machine under the rear extension of the bars 14. Said shaft is journaled in suitable standards 18, 18, secured to and arising from the top of the desk upon which the typewriting machine is supported, and these standards are located a sufficient distance apart to permit of the longitudinal movement of the carriage.

Shaft 17 is provided with a longitudinal groove 19, and a sprocket-wheel 20 is mounted thereon that has a tenon projecting inward from its central opening into the groove 19 so as to permit the sprocket to move longitudinally on said shaft, but be rotatable therewith. Sprocket 20 is provided with an integral disk 21 on the side thereof adjacent to one of the bars 14, and this disk has a circumferential groove in its periphery, and this groove is engaged by a finger 22 the shank of which is secured, preferably, to the extension of the left-hand bar 14, thus, as the carrier of the machine reciprocates longitudinally it causes the sprocket 20 to move longitudinally on the shaft 17 simultaneously therewith.

One end, preferably, the left-hand end, of

the journal 23 of the platen has a milled hand-wheel (heretofore used for rotating the platen) removed, and a sprocket 24 securely mounted thereon which is connected by means of an endless chain 25 to the sprocket 20. These sprockets are of the same diameter, and thus when the platen is rotated shaft 17 will rotate simultaneously therewith and to a corresponding extent.

The left hand end of shaft 17 extends through its bearings and has a sprocket 26 mounted on the same, and this sprocket is connected by means of a suitable chain belt 27 to a sprocket 28 securely mounted on the adjacent end of a horizontal shaft 29 the ends of which are journaled in suitable bearings or hangers 30 secured to the underside of the extension of the top of the desk.

Shaft 29 is disposed in a vertical plane between the longitudinal edges of the slot 5, and about midway of its bearings it is provided with a friction roller 31. The record-strips just below the slot 5 are engaged by this roller 31 and a corresponding idle-roller 32, the shaft of which is arranged parallel therewith, and is journaled in suitable hangers 33 secured to the underside of the top 4 immediately to the rear of slot 5. These rollers 31 and 32 engage the record-strips and through the medium of sprocket and chain mechanism, hereinbefore described, rotate simultaneously and to the same extent as the platen, and draw the record strips downward from the rollers 10 and maintain the slack of the record-strips below the rear extension of the top of the desk all the time.

If desired, the slack of the record-strips below the extension of the top of the desk may be inclosed by a suitable casing 34. The stretch of the record-strips hanging down from the guide-rollers 11 extends in a substantially vertical plane to the bend of the slack portion thereof, and when the carriage of the machine reciprocates, assumes a slight incline in the one direction or the other, according to the movements of the carriage, but does not wrinkle or pucker, owing to the ability of the bend of the slack to tilt or twist in one direction or the other. This feature constitutes the principal improvement in this class of attachments, and while this may be accomplished by other mechanism, I prefer to employ that hereinbefore described.

Suitable manifolding ribbon mechanism, such as are used in other devices of this character, are employed in order that the typewritten matter on the original sheet may be simultaneously written upon the manifold copies or record sheets. Such devices, as shown and described in prior Letters Patents of the United States, Numbers 812,177 and 870,336, granted to me February 13, 1906 and November 5, 1907, respectively.

are preferred, but of course it is understood that any well-known and adaptable mechanism may be employed for this purpose, and I, therefore, do not deem it necessary to 5 herein specifically describe the same.

In the modification disclosed in Fig. 3 of the drawings all the parts are substantially the same as in the form above described, except that instead of mounting the parallel 10 extensions 14 directly upon the carriage of the typewriter, a suitable frame X is substituted therefor that is mounted upon and carried by shaft 17, as shown. This frame X is adapted to be moved through the medium 15 of and longitudinally and parallel with the typewriter carriage 3 by means of suitable arms Y that are secured to the side-frames 15 of said carriage and project to the rear thereof, or by other suitable devices.

20 In order to assist in "registering" or aligning the record strips after the same have been threaded into the typewriter, especially when two or more record rolls are employed, I prefer to divide or separate said strips, 25 in their passage between guide 11 and the idle-rollers 12, by several transversely disposed horizontal rods or rollers x, x, so that when the operator desires to adjust these record strips he holds the registered strips 30 by clamping each between one of his fingers and the respective dividing rod and thereafter draws or pulls the remaining strip or strips under or past the platen until the same are in proper register with the others.

35 After the record strips leave the platen they pass under a suitable cutter-blade and are adapted to be torn off in the desired lengths. For convenience in feeding the paper strips and for rotating the platen, I prefer to 40 mount a milled hand-wheel on the right-hand extended portion of shaft 17 so that by turning the same the platen will be rotated by chain 25 and the feed-rollers 31 and 32 will be actuated through the medium 45 of chain 27.

What I claim as new is:

1. The combination with a writing machine of the kind specified having a rotary platen and means movable with said platen 50 for directing a continuous web of paper thereto, of a roller from which said paper is supplied having stationary bearing the axes of which are parallel to that of said platen and which are situated at the rear 55 of said machine, and means for maintaining a hanging slack portion of said paper between said supply-roller and said machine.

2. The combination with a writing machine of the kind specified having a platen, 60 of a supply roller upon which is mounted a continuous paper strip having stationary bearings adjacent said machine, and means for maintaining a hanging slack portion of said paper strip between said supply roller 65 and the machine.

3. The combination with a writing machine of the kind specified having a platen, of a support for said machine consisting of a flat top having a transversely elongated slot, a supply roller upon which is mounted 70 a continuous paper strip having stationary bearings adjacent said slot, a hanging slack portion of which between said roller and the machine descends down into and up out of said slot, and means for maintaining said 75 slack.

4. The combination with a writing machine of the kind specified having a rotary platen, of a supply roller upon which is mounted 80 a continuous paper strip having stationary bearings adjacent said machine, and means actuated by and rotatable simultaneously with said platen for maintaining a hanging slack portion of said paper strip between said roller and the machine. 85

5. The combination with a writing machine of the kind specified having a reciprocable carriage and a rotary platen journaled therein, and a sprocket wheel on one of its journals, of a supply roller upon which is 90 mounted a continuous paper strip having stationary bearings adjacent said machine, a sprocket actuating said roll, and means including a chain connecting said first-mentioned and last-mentioned sprockets during 95 the reciprocal movements of the carriage whereby a hanging slack portion of said paper strip is constantly maintained between the supply roller and platen.

6. The combination with a writing machine of the kind specified having a reciprocable carriage and a rotary platen journaled therein, a sprocket-wheel on the extended end of one of the journals of the platen, a horizontal shaft back of said machine the axis of which is parallel to that of the platen, a sprocket splined on said shaft and movable longitudinally thereon, but rotatable therewith, and a chain connecting said last-mentioned sprocket and the 100 sprocket on the journal of the platen, of a supply roller upon which is mounted a continuous paper strip having stationary bearings adjacent said horizontal shaft, and means connecting the latter and said roll and 105 rotating the same simultaneously with the platen and adapted to maintain a slack portion of said paper strip between said supply roller and platen. 110

7. The combination with a writing machine of the kind specified having a reciprocable carriage and a rotary platen journaled therein, a sprocket-wheel on the extended end of one of the journals of the platen, a horizontal shaft back of said machine the 120 axis of which is parallel to that of the platen, a sprocket secured to one end thereof, a sprocket splined on said shaft and movable longitudinally thereon but rotatable therewith, and a chain connecting said last-men- 125 130

tioned sprocket and the sprocket on the journal of the platen, of a supply roller upon which is mounted a continuous paper strip having suitable bearings adjacent said horizontal shaft, feed rollers, a sprocket that actuates said feed rollers, and a chain connecting said last-mentioned sprocket and the sprocket on the end of said shaft.

8. The combination with a writing machine of the kind specified having a reciprocable carriage and a rotary platen journaled therein, and a sprocket wheel on one of its journals, of a series of supply rollers upon which are mounted continuous paper strips having suitable stationary bearings adjacent said machine, a sprocket through the medium of which said rolls derive motion, and means including a chain connecting said first-mentioned and last-mentioned sprockets during the reciprocable movements of the carrier whereby a slack portion of said paper strips is constantly maintained between the supply roller and platen.

9. The combination with a writing machine of the kind specified having a reciprocable carriage, a rotary platen journaled therein, and a sprocket on one of the journals of the platen, of a support for said machine consisting of a platform having a transversely elongated slot therein adjacent said machine, a supply roller upon which is mounted a continuous paper strip journaled next the rear edge of said slot, a sprocket rotating said roller, and means including a chain connecting said first-mentioned and said last-mentioned sprockets whereby a slack portion of said strip is constantly maintained that descends into and out of said slot.

10. The combination with a writing machine of the kind specified having a reciprocable carriage, a rotary platen journaled therein, of a support for said machine consisting of a platform having a transversely elongated slot therein adjacent said machine, a horizontal shaft rotated by said platen having stationary bearings and located adjacent said machine and in front of said slot, a sprocket splined on said shaft movable longitudinally thereon but rotatable therewith, a supply roller upon which is mounted a continuous paper strip journaled next the rear edge of said slot, a sprocket rotating said roller, and means including a chain connecting said first-mentioned and said last-mentioned sprockets whereby a slack portion of said strip is constantly maintained that descends into and out of said slot.

11. The combination with a writing machine of the kind specified having a reciprocable carriage, a rotary platen journaled in said carriage, guide-rollers the bearings

of which are carried by said carriage and which are located adjacent said platen and direct a continuous strip of paper thereto, of a supply roller upon which is mounted said continuous strip of paper having stationary bearings adjacent said machine, and means actuated by said platen for maintaining a hanging slack portion of said strip between the supply roller and said guide-rollers.

12. The combination with a writing machine of the kind specified having a reciprocable carriage, a rotary platen journaled in said carriage, guide-rollers the bearings of which are carried by said carriage and which are located adjacent said platen and direct continuous strips of paper thereto, and a series of idle-rollers interposed between the guide-rollers and platen that separate said strips, of supply rollers upon which are mounted said continuous strips of paper journaled adjacent said machine, and means actuated by said platen for maintaining a slack portion of said strips between the supply rollers to said guide-rollers.

13. The combination with a writing machine of the kind specified having a reciprocable carriage, a rotary platen journaled in said carriage, a sprocket on one of the journals of said platen, guide-rollers the bearings of which are carried by said carriage and which are situated adjacent said platen and direct a continuous strip of paper thereto, of a supply roller upon which is mounted said continuous paper strip, devices for rotating the same, and means including a chain for transmitting the movement of the platen sprocket to said devices.

14. The combination with a writing machine of the kind specified having a reciprocable carriage having a finger depending from one end thereof, a rotary platen journaled in said carriage, guide-rollers the bearings of which are carried by said carriage and are located adjacent said platen, and direct a continuous strip of paper thereto, of a horizontal shaft having stationary bearings back of said machine and actuated by and simultaneously with the platen, a rotatable device carried by said shaft and engaged by said finger which is adapted to move therewith, a supply roller upon which is mounted said continuous paper strip, a sprocket for rotating the same, and means including a chain for transmitting the motion of said shaft to said roller.

In witness whereof I have hereunto set my hand this 23rd day of December, 1913.

ENGLAND J. BARKER.
